United States Patent Office

Des. 186,446
Patented Oct. 27, 1959

186,446

GUN SUPPORT

Paul J. Moynihan and Harry Nick, Milwaukee, Wis., assignors to Seaway Industries, Inc., Milwaukee, Wis., a corporation

Application April 24, 1958, Serial No. 50,595

Term of patent 14 years

(Cl. D30—1)

Fig. 1

Fig. 3

Fig. 2

Figure 1 is an end elevational view in perspective of a gun support, showing our new design;

Figure 2 is a rear elevational view in perspective; and Figure 3 is a front elevational view in perspective.

We claim:

The ornamental design for a gun support, as shown.

References Cited in the file of this patent

UNITED STATES PATENTS

D. 26,770	Webber	Mar. 16, 1897
D. 131,045	Johnson	Jan. 6, 1942
2,520,285	Olson	Aug. 29, 1950